(57) **CLAIM**

The ornamental design for a dispenser, as shown and described.

DESCRIPTION

FIG. 1 is a perspective view of a dispenser; FIG. 2 is a front elevation view of the dispenser shown in FIG. 1;

FIG. 3 is a rear elevation view of the dispenser shown in FIG. 1;

FIG. 4 is a top plan view of the dispenser shown in FIG. 1; FIG. 5 is a bottom plan view of the dispenser shown in FIG. 1;

FIG. 6 is left-side elevation view of the dispenser shown in FIG. 1; and,

FIG. 7 is right-side elevation view of the dispenser shown in FIG. 1.

The dashed lines immediately adjacent to the shaded areas in the figures represent the boundaries of the claimed design. The dashed lines in the figures illustrate the portions of the dispenser that form no part of the claimed design. None of the broken lines form any part of the claimed design.
